UNITED STATES PATENT OFFICE.

MARTIN NEKOLAI ERICKSON, OF COLUMBIA FALLS, MONTANA.

WRENCH.

Application filed February 9, 1922. Serial No. 535,263.

To all whom it may concern:

Be it known that I, MARTIN N. ERICKSON, a citizen of the United States, and a resident of Columbia Falls, in the county of Flathead and State of Montana, have invented certain new and useful Improvements in Wrenches, of which the following is a specification.

This invention relates to wrenches, and 10 more particularly to ratchet wrenches of the kind employing a brace, and the object thereof is to provide a wrench having a brace of novel shape or formation so as to especially adapt the same for use in connection with the nuts of the fourth connecting 15 rod of a Ford car, or the like, although it is obvious that the device may be used wherever practical in inaccessible places.

Other and further objects of my invention will become readily apparent to persons skilled in the art, from a consideration of the following description when taken in conjunction with the accompanying drawings, wherein:

25 Figure 1 is an elevation of the improved wrench.

Figure 2 is a face view of the wrench head or socket, and

30 Figure 3 is a sectional view taken on the line 3—3 of Figure 1.

Referring to the drawings in detail, in which like reference characters designate corresponding parts throughout the several views, my improved device is shown as comprising a sweep or brace 10 consisting of an axial portion or stem on which is mounted a swiveled knob or handle 12, the latter being preferably of wood and having a metal bearing and sleeve connection 13 by 35 which the same is adapted to be held stationary while the sweep is operated by oscillating or working the same back and forth, or rotating it where such is possible. The sweep or brace 10 is formed of a bar or section of metal of suitable strength such as 40 steel, and is extended outwardly at an obtuse angle but substantially at right angles to the stem or shank 11, as indicated at 14 and the bight or gripping portion thereof 45 is then extended substantially at right angles but parallel to the shank or stem 11, as indicated at 15, and then at an obtuse angle so as to diverge from the portion 14 substantially at right angles to the portion 15, as indicated at 16, the divergence from

the connecting portion or bight 15 or the convergence of the portions 14 and 16 toward the bight or connecting portion 15 accommodating the hand during the use of the wrench. The sweep 10 as thus constructed 60 is of U-shaped form, the portion 15 constituting the body of the sweep, the portion 14 the long leg thereof and the portion 16 the short leg thereof.

At a point spaced from the axis of the 65 shank or stem 11, the portion 16 is bent parallel to the portions 11 and 15, a short distance, as indicated at 17 and then at right angles toward the axis of said shank or stem 11 as indicated at 18 where it is provided with a reversible ratchet construction 70 19 consisting of a reversing ratchet sleeve or dog 20 having pawls 21 co-operating with the ratchet teeth 22, as is well known in the art. The portions 17 and 18 constitute an 75 angular extension. The head 23 of the wrench is provided with a socket 24 for accommodating a nut, the same being of hexagonal or other shape, but especially hexagonal for use in connection with the fourth 80 connecting rod of a Ford car. By this construction, the socket can be readily applied to the connecting rod cap nuts which renders them easily accessible from the bottom portion of the motor by removing the crank 85 case at the bottom, or the plate thereof, so that the nuts may be either tightened or loosened by working the sweep or brace part forward or backward by oscillating the same through the medium of the ratchet mechanism. By reversing the position of the sleeve, the ratchet device may be reversed 90 so that the nuts may be loosened or tightened as desired.

The advantages of this design of a wrench 95 is that after it is adjusted to the nut of the fourth connecting rod, it can be held in perfect alignment with the nut under the most severe conditions while the same is being turned off or on. The long sweep with the 100 knob to support the same gives the user great leverage which is very important in a wrench for this purpose, the knob or handle being held in one hand while the sweep is operated. The wrench is inexpensive to 105 manufacture and will meet with every garage man's and Ford owner's approval as it will reduce the cost of having the connecting rods adjusted at least one-half, and the work will be a pleasure instead of a 110

source of much energy and bruising of hands as well as pinching of fingers.

In view of the foregoing it is thought that the operation of the device will be readily understood and in view of the simplicity and practical value that it will readily commend itself to those skilled in the art.

Having thus described my invention, what I claim is:—

- 10 In a wrench of the character described, a handle, a socket, said handle and said socket being spaced and axially alined, a U-shaped sweep having a long leg provided with a stem at its outer end, said stem being

axially alined and having swivelled connection with the handle, said sweep also having a short leg provided with an angular extension including a portion extending parallel to the axis of the handle and socket and a portion extending at right angles from the outer end of said first mentioned portion and toward the common axis of the handle and socket, and a ratchet connection directly connecting the outer end of the last mentioned portion of the angular extension 25 and the socket.

MARTIN NEKOLAI ERICKSON.
